UNITED STATES PATENT OFFICE.

DONALD A. CLARKE, OF SEDALIA, MISSOURI.

DESIGN FOR A BRACKET.

SPECIFICATION forming part of Design No. 15,186, dated August 5, 1884.

Application filed April 17, 1884. Term of patent 14 years.

To all whom it may concern:

Be it known that I, DONALD A. CLARKE, a citizen of the United States, residing at Sedalia, in the county of Pettis and State of Missouri, have invented and produced a new and original Design for Brackets, of which the following is a specification, reference being had therein to the accompanying drawings, in which—

10 Figure 1 is a perspective view of my newly designed bracket. Fig. 2 is a top or plan view thereof.

The leading features of my design consist in a right-angular-shaped body, perpendicular sides comprised therein and having suitable ornamental molding, and a molding at the bottom from which depends a fringe.

Referring to the drawings, A designates the body of the bracket, which is of re-entrant right-angular form and comprises perpendicular sides a , and a right-angular top, a' , as shown in the annexed drawings. Suitable molding in the form of longitudinal ribs, as shown at a^2 , is provided upon the perpendicular sides, and from the bottom edge of the body

A projects a molding, B, of any suitable design. A fringe, C, depends from the bottom edge of this molding, as shown. Each end of the bracket may be ornamented with a projection or knob, a^3 , of suitable design, whereby the said ends will present to the eye the effect or design of a drawer face.

I claim as my invention—

1. A design for a bracket, consisting of a re-entrant right-angular body having a corresponding top and perpendicular sides provided with ornamental molding, as set forth. 35

2. The herein-described design for a bracket, consisting of the right angular body having perpendicular sides provided with molding, as shown, a molding extending around the bottom edge of the body, and a fringe depending from the bottom edge of the molding, substantially as set forth. 40

In testimony whereof I affix my signature in presence of two witnesses.

DONALD A. CLARKE.
